UNITED STATES PATENT OFFICE.

BERNARD U. POTTER, OF HOLYOKE, MASSACHUSETTS, ASSIGNOR TO WORTHINGTON PUMP AND MACHINERY CORPORATION, A CORPORATION OF VIRGINIA.

MULTIPLE PISTON OR BUCKET PUMP.

1,249,665.

Specification of Letters Patent. Patented Dec. 11, 1917.

Application filed December 27, 1916. Serial No. 139,088.

To all whom it may concern:

Be it known that I, BERNARD U. POTTER, a citizen of the United States, residing at Holyoke, county of Hampden, and State of Massachusetts, have invented a certain new and useful Improvements in Multiple Piston or Bucket Pumps, fully described and represented in the following specification and the accompanying drawings, forming a part of the same.

This invention relates to that class of pumps used especially for deep well pumping in which a plurality of reciprocating buckets or plungers act on the liquid successively, and each bucket rod passes through the bucket rods of the buckets above it. In these constructions differential plunger actions have been set up due to the fact that each bucket rod is increased in size in order to contain the bucket rods of the buckets below it, and thereby each bucket above the bottom bucket has been decreased in capacity to such an extent that they have necessarily discharged unequal quantities of the fluid pumped. The object of the present invention is to overcome this differential plunger action and to provide an improved power pump of this class in which the discharge from each bucket shall be the same without diminishing the total volume handled by the pump.

In the accompanying drawings forming a part of this specification, a triple acting deep well pump embodying the invention in its preferred form is shown, and this construction will now be described in detail and the features forming the invention then specifically pointed out in the claims.

In the drawings:—

Figure 1 is a front view of the pump with the pump head in elevation and the pump well in section.

Fig. 2 is a diagrammatic view showing the arrangement of the crank head pins in respect to the center line of the crank shaft.

Referring to the drawings, the frame 10 of the pump head is mounted above the well 11, and carries the crank shaft 12, shown as driven by gear 13 from power shaft 14 and pinion 15. The crank shaft 12 carries three separate cranks for operating the buckets, these cranks being set 120 degrees apart, and connected to the respective buckets as follows:—The middle crank 16

is connected by its crank rod 17 and sliding crosshead 18 directly to bucket rod 19 connected to bottom or outer bucket 20. Outside the crank 16 are the cranks 21, 21 connected by their crank rods 22, 22 and sliding crossheads 23, 23 to rods 24, 24 and yoke 25 attached to the tubular bucket rod 26 which in turn carries the intermediate bucket 27. Outside the cranks 21 are the cranks 28, 28 connected to their crank rods 29, 29 and sliding crossheads 30, 30 to rods 31, 31 and yoke 32 to which is attached the tubular bucket rod 33 which carries the top or inner bucket 34. The rod 33, with the inclosed concentric rods 26 and 19, moves through the discharge head 35 at the top of the drop tube 36 within the well, a suitable stuffing box 37 being provided and the discharge head 35 having a delivery pipe 38. The pump as thus far described is that of United States Letters Patent No. 1,102,583, dated July 7, 1914, but it will be understood that this pump is shown only for illustration, and that the present invention is applicable also to multiple piston or bucket pumps of other types.

The present invention relates to the increasing or decreasing of the bucket strokes to thereby increase or decrease the discharge of each individual bucket, so that all the buckets shall carry and discharge an equal quantity of fluid. This is done by varying the stroke so as to compensate for the space occupied by the bucket rods for the different buckets.

In the pump illustrated this is accomplished by making the cranks of such length as to give the several working rods and buckets different lengths of strokes.

Referring to Fig. 2, which is a diagrammatic view of the location of the crank pins 95 with regard to the center 12' of the crank shaft, the crank pins 21' of the intermediate bucket are so placed with regard to the crank shaft center as to give the required nominal length stroke. Because of the increased size of the largest bucket rod 33, the length of the bucket stroke of the upper bucket is increased by increasing the crank length, the crank pins 28' being farther away from the crank shaft center and, as 105 the bucket rod 17 of the lower bucket is smaller than the other bucket rods the crank of the lower bucket 20 is shorter, its pin 16'

being nearer the crank shaft center, so as to give a shorter stroke, such as to carry and deliver the same amount of fluid as bucket 27. The delivery of the pump is the same, 5 therefore, as in present pumps having the same nominal stroke.

The preferable application of the invention to pumps having a larger or smaller number of buckets is as follows:—In a two 10 bucket pump the stroke of the bottom bucket preferably will be decreased below nominal and the upper bucket increased above the nominal. In a four-bucket pump, the stroke of the two lower buckets 15 preferably will be decreased below and the stroke of the two upper buckets increased above the nominal.

It will be understood that the invention is not limited to a vertical pump nor to the 20 form of actuating mechanism shown, but that it is applicable generally in multiple piston or bucket pumps, as defined by the claims.

What I claim is:

1. A pump having a plurality of buckets 25 or plungers arranged in line with the bucket rods of the outer buckets passing through the bucket rods of the inner buckets, and means for actuating the inner buckets with a longer stroke than the outer 30 buckets to compensate for the decrease in capacity due to the increased size of the bucket rods of the inner buckets.

2. A pump having a plurality of buckets 35 or plungers arranged in line with the bucket rods of the outer buckets passing through the bucket rods of the inner buckets, and cranks and connections for operating the buckets, the cranks for the successive buckets being increased in length from the outer 40 bucket inward to compensate for the decrease in capacity due to the increased size of the bucket rods of the inner buckets.

In testimony whereof, I have hereunto set my hand.

BERNARD U. POTTER.
